UNITED STATES PATENT OFFICE.

MILES S. HOLLIS, OF NEW YORK, N. Y.

STOP-COCK.

1,134,678.

Specification of Letters Patent.

Patented Apr. 6, 1915.

Application filed January 31, 1913. Serial No. 745,411.

To all whom it may concern:

Be it known that I, MILES S. HOLLIS, a citizen of the United States, and a resident of New York, borough of Brooklyn, county of Kings, and State of New York, have invented certain new and useful Improvements in Stop-Cocks, of which the following is a full, clear, and exact description.

This invention relates more particularly 10 to safety stop cocks for use in connection with gas fixtures.

The primary object of the invention is to provide simple and efficient means whereby the plug or valve member is not likely to be accidentally operated to turn on the gas as 15 very often happens and which is liable to cause accidents often resulting in the loss of life.

Another object of the invention is to provide simple and efficient means for operating 20 the plug or valve member which is normally free and requires a special movement to place the same in operative relation with the plug or valve member before the same 25 can be moved and which, immediately the plug or valve member has been operated to turn on or turn off the gas and the operating means released, will return to an inoperative position.

30 A further object of the invention is to provide simple and efficient means which may be readily applied to devices of this kind as ordinarily constructed without making any great change in the parts as ordinarily constructed.

35 A still further object of the invention is to provide an additional safety device and to provide means whereby the valve operating means may be held against movement.

40 With these and other objects in view, the invention will be hereinafter more particularly described with reference to the accompanying drawings, which form a part of this specification, and will then be pointed 45 out in the claims at the end of the description.

In the drawings, Figure 1 is a vertical section, partly in elevation, of one form of cock embodying my invention. Fig. 2 is a 50 sectional plan view taken on the line II—II of Fig. 1. Fig. 3 is a sectional plan taken on the line III—III of Fig. 1. Fig. 4 is a section taken on the line IV—IV of Fig. 1.

While the invention is shown as applied 55 more particularly to a stop cock adapted for gas fixtures, it will be understood that the

invention is applicable to various forms and constructions of valves or like devices wherein safety means is desirable to prevent the accidental turning on or turning off of the medium controlled by said device.

The body or casing 10 may be held to the gas or other pipe 11 and has an opening 12 for the passage of the gas or other medium to be controlled. A tapered opening extends transversely of the opening 12 and fitting this tapered opening is a plug or valve member 13. The valve member 13 is held within the opening by a screw 14 or otherwise and is provided with an opening 15 therethrough which is adapted to be brought into communication with the opening 12 of the casing 10 to permit the medium to flow therethrough or to be partly rotated to the position shown, in which case the medium will be shut off. The parts as thus described may be of the usual or of any preferred construction.

A sleeve member 16 has one end threaded and this threaded end is adapted to engage a threaded portion 17 on the valve casing 10 so as to be rigidly though detachably secured thereto. The sleeve member 16 is recessed to provide an opening or chamber 18 and communicating with this chamber is a smaller opening 19 through which the stem 20 of an operating device 21 is adapted to pass. This operating device 21 has a handle portion 22 at one end and at its other end is enlarged somewhat to provide a head 23. This head 23 is slotted across the end of the same, as at 24, and said slot is adapted to fit over a projection 25 on the end of the plug or valve member 13. The part 25 is substantially rectangular in form and is adapted to fit in the slot 24 when the operating device is moved upward, and in this position the valve or plug 13 may be rotated either to shut off or to permit the medium to flow through the casing 10. The operating device 21 has its stem portion loosely fitting the opening 19 so that said operating device as soon as it is released will, by gravity, move to the position shown in Fig. 1, out of the path of the plug and the projection 25 thus being entirely free of the plug so that it cannot be operated in either direction unless said device is again placed in operative relation therewith.

As a safety means and to prevent the liability of the accidental movement of the valve or plug 13, I provide a safety member

or element 26. This element is in the form of a rod which is adapted to move lengthwise of the stem 20. The device 26 is somewhat longer than the stem 20 of the operating device 21 and at one end is provided with a knob 27 and its other end with an enlarged head or flange 28. The device 26 is adapted to move freely within the stem 20 of the operating device, and being longer than said device, any other object which might contact with the device 21 and cause an accidental movement thereof, will naturally first engage the device 26 and shift the same so that it will be less likely that the device 21 will be at all disturbed.

The head portion 23 of the device 21 is provided on the underside thereof with a plurality of teeth 29, which are adapted to enter spaces between the teeth 30 on the lower part of the chamber or opening 18, thus when the operating device is in the position shown in Fig. 1, the teeth 29 of said device will engage the teeth 30 of the sleeve 16, thus preventing any rotary movement whatever of the device 21 until the same is forced away from said device toward the plug. By this means the operating device is not only held against movement in one direction and the liability of its independent movement reduced to a minimum, but the said operating device requires a special manual manipulation independent of its rotary movement before the valve or member 13 can be rotated.

From the foregoing, it will be seen that simple and efficient means is provided whereby a stop cock may be prevented from being accidentally operated; that simple means is provided whereby the valve or plug member may be readily operated; that said cock is simple in construction and adds very little if any additional cost to the ordinary form of device of this kind; and that said device is effective in use and serves to avoid the liability to accidents by the accidental turning on of the gas or any other medium to be controlled.

Having thus described my invention, I claim as new and desire to secure by Letters Patent:

1. A device of the character described, comprising a casing, a valve plug for controlling the medium passing through said casing, a gravity rotary operating device for the plug adapted to be moved therefrom, and a slidable rod mounted axially of the valve and somewhat longer than the operat-

ing device and freely slidable therein and having one end normally projecting beyond said operating device.

2. In a stop cock, the combination of a casing, a valve member arranged in said casing and adapted to control the medium passing therethrough and having an elongated projection at one end, a sleeve having a portion thereof forming an annular chamber, a rotary device having a slotted end adapted to engage the projection to rotate the same and adapted to move therefrom by gravity, and a rod somewhat longer than the rotary device and having one end normally projecting beyond the operating device and adapted to engage a part of the plug if moved lengthwise of the operating device.

3. In a stop cock, the combination of a casing, a valve member arranged in said casing and adapted to control the medium passing therethrough and having an elongated projection at one end, a sleeve, a rotary device adapted to rotate the valve member, and a slidable rod mounted axially of the valve and somewhat longer than the rotary device and having one end normally projecting beyond the rotary device.

4. In a stop cock, the combination of a casing, a valve member arranged in said casing and adapted to control the medium passing therethrough and having an elongated projection at one end, a sleeve, a rotary device having a part projecting beyond the sleeve to rotate said valve member, and slidable means mounted axially of the valve and freely slidable in the rotary device and somewhat longer than the rotary device and having a part normally projecting beyond the same.

5. In a stop cock, the combination of a casing, a valve member arranged in said casing and adapted to control the medium passing therethrough and having an elongated projection at one end, a sleeve, a rotary device passing through the sleeve and having a slotted end adapted to engage the projection to rotate the valve member, and a slidable rod mounted axially of the valve and freely slidable in and somewhat longer than the rotary device and having one end normally projecting beyond the same.

This specification signed and witnessed this 29th day of January A. D. 1913.

MILES S. HOLLIS.
